AUTOMATIC PIN SETTING DEVICE FOR
HOLDING MATERIALS FOR SEWING

Morris S. Malek, Ridgefield, N. J.

Application October 12, 1937, Serial No. 168,586

14 Claims. (Cl. 223—37)

This invention relates to new and useful improvements in a device for holding materials for sewing, particularly, tie material.

More specifically, the invention provides for a plurality of pin setting devices attached to a table and which are adapted to insert pins into aligned sections of tie material for holding these materials in their aligned positions so that they may be sewn by hand or upon a conventional sewing machine, after which the pins may be removed.

Another object of the invention is the construction of a pin setting device in the normal position of which the device swings away from the top of the table permitting the top to be free from any interfering members so that the operator of the machine may easily align the pieces of material into which it is desired to insert the pins.

Still further it is proposed to provide a novel type of pin holder which is adapted to grasp one of the ends of the pin to hold it in a horizontal position so that it may be moved laterally for inserting the pins into the cloth.

Another object of the invention is to provide a construction in which a continuous roll of wire may be substituted for separate pins and which may be cut into small sections for insertion into the aligned materials.

Another object of the invention is to so construct the pin inserting devices that they may be out of their normal aligned positions so that they may be used for inserting pins into curved seams.

Still further it is proposed to introduce a new and novel device for reversing neckties and which consists of a spiral shaped spring attached to a flat member and which is adapted to be inserted into the small end of the tie for positioning the tie upon the flat member so that the wide end of the tie may be passed over the narrow end.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an end elevational view of the automatic pin setting device according to this invention.

Fig. 2 is a plan view of Fig. 1.

Fig. 3 is a sectional view taken on the line 3—3 of Fig. 2.

Fig. 4 is a view of a portion of Fig. 2 showing the folded position of the tie covering material.

Fig. 5 is a sectional view taken on the line 5—5 of Fig. 2.

Fig. 6 is a view of a portion of Fig. 5 partly in section and showing another position of the parts.

Fig. 7 is a plan view of Fig. 6 partly in section.

Fig. 8 is an elevational view of the pin holder per se.

Fig. 9 is a view looking in the direction of the line 9—9 of Fig. 8.

Fig. 10 is a view looking in the direction of the line 10—10 of Fig. 8.

Fig. 11 is a sectional view taken on the line 11—11 of Fig. 6.

Fig. 12 is a sectional view taken on the line 12—12 of Fig. 11.

Fig. 13 is an enlarged view of one of the pins used in this device.

The automatic pin setting device for holding materials for sewing consists of a table 10 having a guide gauge 11 mounted thereon and against which a lining 12 and covering material 13 of a tie may be positioned. Holding strips 14 are engageable over the lining and covering materials for holding the materials in position while the covering material 13 is being folded upon itself. A plate 15 is slidably mounted on the top of the table 10 and has one of its edges 15^a engaging beneath a portion of the covering material 13 so as to fold the covering material over the holding strips when the plate 15 is manually moved rearwards. A manually operable means for inserting pins into the material at spaced positions for holding the materials in their folded positions is pivotally mounted on the table, as will be herein-after set forth.

The table consists of a table top having a substantially flat surface and provided with a resilient covering 18^a upon which the lining and covering materials may be positioned. It has legs 10^b for supporting the table 10 at a position in which it is convenient for the operator to align the materials and also operate the pin setting device. The holding strips 14 consists of end sections 14^a which are pivotally mounted on the ends of the table 10 by means of hinges 16 and are provided with extending portions 14^b extending at right angles to the end section 14^a and have their ends abutting each other at about the center of the table top 10. With this arrangement it is possible to pivotally raise the holding strips 14 after the pins have been inserted into the covering material 13 to withdraw 55

the tie from the strips. Inasmuch as the tie material is obviously flexible, this step is accomplished by simply grasping the central portion of the tie and slidably raising it off the strips 14.

5 The holding plate 15 comprises a piece of substantially flat material provided with an upturned edge 15^b by which the plate may be grasped for manually moving it rearwards. The table top 10 is provided with elongated slots 17 through which pins 18 from the plate 15 project and which act to guide the plate 15 in its forward and rearward movement for properly folding the covering material 13 over the holding strips 14.

15 The means for inserting the pins into the material consist of a plurality of separate devices connected together for simultaneous operation, and each of these devices consists of a bracket 19 which is pivotally mounted by means of a stud 20 upon a lug 21 extending from the face of a plate 22 which is attached at the rear of the table 10. A member 23 is pivotally mounted intermediate of its ends on the bracket 19 by means of a stud 24 and has one of its ends 23^a extending over the table 10. A resilient means consisting of a spring 25 extends between a screw 26 engaging through a portion of the bracket 19 and an eye member 27 attached to the underside of the member 23. A rod 28 is slidably mounted 20 through the other end 23^b of the member 23. A stop pin 29 is fixedly attached to a portion of the plate 22 above the pivot point of the bracket 19 for limiting the turning of this bracket. Means are provided for moving the rod 28 to turn the bracket 19 until it strikes the stop 29 to limit its pivoting so as to pivot the member 23 on the bracket 19 against the action of the resilient spring 25 until the bottom of the member 23 strikes against the aligned materials positioned 30 upon the top of the table 10.

35 Pins 30 are contained within a pin supply 31 in the end 23^a of the member 23 and a pin holder 32 is mounted on the member 23 and has opposed holding jaws 32^a for receiving and holding the end of one of the pins 30. Means are provided 40 for moving the pins downwards from the pin supply into a position in which one of its ends will be between the jaws 32^a. Other means move the pins laterally, operable only after the member and the bracket have ceased pivoting, as will be seen, for forcing the pins into the tie materials for holding the materials in their aligned positions. The pins are pointed at each end and, in a preferred form, are provided with annular 45 grooves 30') at each end (Figure 13) to interrupt the smooth surface of the pin, and thus better insure that the pins will stay in the fabrics until 50 they are ready to be pulled out.

55 The bracket 19 has lug portions 19^a by which 60 it is pivotally mounted on the lugs 21 of the plate 22 and other lug portions 19^b upon which the member 23 is pivotally mounted. An extended portion 19^c of the bracket 19 is provided with a threaded opening through which the screw 26 65 may be passed and against which the member 23 strikes when the spring 25 draws these two members together. This screw 26 may be adjusted to control the relative positions of the member 23 and the bracket 19 for controlling the 70 distance through which the member 23 will move with relation to the bracket 19.

75 The means for moving the rod 28 to pivot the bracket 19 and the member 23 consists of a shaft 33 which is rotatively mounted in brackets 34^a attached to the rear faces of the rear legs 10^b.

A radial arm 34 has one of its ends fixedly attached to the shaft 33 and a link 35 has its ends pivotally attached to the other end of the radial arm 34 and the lower end of the rod 28 for pivoting the bracket 19 and the member 23. A foot 5 pedal 36 is fixedly attached to the shaft 33 and extends to the front of the table 10 and is provided with an enlarged portion 36^a upon which one's foot may be placed for pressing the foot 10 pedal 36 downward to turn the shaft 33, which 15 in turn raises the radial arms 34 upwards (see dot and dash line 34' in Fig. 5) to cause the link 35 to act against the bottom end of the rod 28 to pivot the bracket 19 until it strikes the stop 29 for limiting the pivoting of this bracket and 15 causing the member 23 to pivot on the bracket 19.

The means for moving the pin downwards from the pin supply to a position in which its end will be between the jaws 32^a consists of a vertical 20 slot 37 formed within the end 23^a of the member 23 and which connects with the lower end of the pin supply 31. This pin supply 31 consists of an enlarged opening 31^a and a smaller opening 31^b. A passage 31^c connects the larger opening with 25 the smaller opening and another opening 31^d connects the smaller opening with the slot 37. The purpose of having the two openings connected by the narrow slot, which in turn is connected by another narrow slot with the slot 37, 30 is to prevent the pins from jamming on the top of the jaws 32^a and for limiting the passage of these pins. It will be noted that the pins will come out upon the top of the jaws 32^a in a single 35 file after each downward motion of a plate 38 which is slidably mounted within the slot 37.

This plate 38 is fixedly attached to a member 39 which has its top end pivotally connected with a lever 40 which is pivotally mounted intermediate of its ends upon a lug 41 formed upon 40 the member 23 and a stud 42 is passed through these parts to accomplish the pivotal mounting. A rod 43 is slidably mounted within the member 23 and has its ends extending from the top and bottom of the member 23. The top end of the 45 rod 43 is provided with a cam 44 adjustably mounted thereon and which engages a complementary cam recess 45 formed on the adjacent end of the lever 40 for pivoting the lever 40 as the rod 43 moves up and down to cause the plate 38 50 to move similarly. The cam 44 is mounted upon the end of the rod 43 by means of opposed nuts 46 which threadedly engage this extended end and which may be adjusted to change the position of the cam 44 with relation to the rod 43 to control 55 the distance through which the lever 40 will pivot when the rod 43 moves up and down.

The other end of the rod 43 is provided with a ball bearing 47 which is adapted to engage a portion of the bracket 19, and when the member 23 60 pivots on the bracket 19 the ball bearing will ride on the bracket and cause the lever 43 to be urged upwards, which in turn will pivot the rod 40 causing the plate 38 to move downwards forcing the pin downward between the jaws 32^a 65 of the pin holder to a position in which it may be easily passed into the tie material.

Plugs 48 are engaged into the ends of the opening in the member 23 through which the rod 43 passes, and the rod 43 is provided with a shoulder 70 49 intermediate of its ends. A spring 50 operates between one of the plugs 48 and the shoulder 49 to urge the rod 43 downwards to a position in which the ball bearing 47 will bear against the bracket 19. A spring 51 is mounted within an 75

enlarged portion 37^a of the slot 37 and operates between the bottom of this enlarged portion and a pin 52 extending from the plate 38 and tends to normally push the plate 38 upward within 5 the groove 37. Thus it will be seen that the action of the springs 50 and 51 will tend to cause the members of the pin moving device into a position in which the slightest movement of the member 23 on the bracket 19 after this bracket 10 has ceased to pivot, will cause these members to operate forcing the pins 30 downward between the jaws 32^a of the pin holder 32. This pin holder 32 consists of jaw portions 32^a one of which continues into a portion 32^b extending 15 upward at an angle to the jaws 32^a. The portion 32^b continues into another portion 32^c which extends upward at an angle from the portion 32^b and which is parallel with the jaws 32^a.

This pin holder 32 is mounted within a cavity 23^c and the portion 32^c is provided with an elongated slot 53 through which a screw 54 may be passed. The screw 54 threadedly engages into the end 23^a of the member 23 and is adapted to hold the pin holder 32 in various adjusted positions 25 upon the member 23 to control the positioning of the pins 31 with relation to the material in which the pins are to be inserted.

The top face of the table 10 has a cam 55 which engages a complementary cam recess 56 formed 30 in the bottom face of the member 23. This cam is adapted to force the material into a curved position at the end of the pin 30 which is held between the jaws 32^a of the pin holder 32 so that when the pin 30 is moved laterally, it will be 35 forced through the curved portions of the materials. The means for moving the pins laterally consists of a member 57 which engages the free end of the pin 30 and which is adapted to move laterally for correspondingly moving the pin 30 40 laterally. This member 57 has an upwardly extending stud 58. A lever 59 is pivotally mounted upon the bottom face of the member 23 and has a slot 60 into which the stud 58 engages for moving the member 57.

45 A bell crank 61 is pivotally mounted intermediate of its ends by means of a pin 62 and has one of its ends provided with a reduced portion 63 which engages an opening 64 in the lever 59 for pivoting the lever when the bell crank is moved. The other end of the bell crank 61 is engaged 50 over the upper end of the rod 28 and is positioned within a tensioning device for holding the bell crank 61 in its normal position as shown in full lines in Fig. 6. This tensioning device consists of 55 a collar 65 fixedly attached to the rod 28 by means of a pin 66 and opposed conical shaped members 67 are mounted upon the rod 28. A spring 68 is coaxially mounted on the rod 28 and operates between the lower conical shaped member 67 and the collar 65 for urging the conical members 67 together. The end of the bell crank 61 has an elongated slot 69 which engages over the upper end of the rod 28 and between the conical members 67. The top of the rod 38 is provided 65 with nuts 70 which bear against the topmost conical member 67 and which may be adjusted with relation to the rod 28 for increasing or decreasing the tension with which the spring 28 will bear against the lowermost conical member 67.

70 A spring 71 having a tension greater than the spring 25 is mounted on the lower end of the rod 28 and operates between the bottom face of the member 23 and an enlarged portion of the rod 28 for preventing this rod from moving upwards 75 with relation to the member 23 for preventing

the bell crank from being pivoted until the bracket 19 and the member 23 have ceased pivoting. After these members have ceased pivoting it is still possible to depress the foot lever 36 to urge the rod 28 upward to pivot the bell crank 61, 5 which in turn pivots the lever 59 and which in turn causes the member 57 to move laterally for correspondingly moving the pin 30 to engage the pin into the portions of the material which have been folded over the cam 55. As shown in Fig. 10 2 there are a plurality of these pin setting devices which are connected together by means of a bar 72 attached to the bottom faces of the members 23 for causing these devices to move simultaneously when the foot pedal 36 is depressed. 15

The operation of the device is as follows:—

Assuming that the parts are in their normal 20 positions, shown by the full lines in Fig. 5, a plurality of pins 30 are put into the pin supply 31 formed at the front end of the member 23, and the lining and covering materials are placed in their aligned positions on top of the table 10 with relation to the guide 11. The plate 15 is moved rearwards to cause the front edge of the covering 25 material 13 to be folded over the holding strips 14 which have been positioned upon the aligned materials and the foot pedal 36 is depressed causing the bracket 19 to pivot until it strikes the stop pin 29 (see dot and dash lines in Fig. 5). 30 The member 23 pivots on the bracket 19 until it strikes the top of the cloth materials which have been positioned on the table 10 (see full lines in Fig. 6). During the time that the bracket 19 35 ceased pivoting and while the member 23 is pivoting, the rod 43 is being urged upwards to cause the lever 40 to be pivoted to force the plate 38 downwards against the holding action of the spring 50 to press the lowermost pin at the end of the passage 31^d down on the pin holder 32 40 until one of its ends engages between the jaws 32^a and the other of its ends rests on the member 57. After the member 23 has ceased pivoting the foot 45 pedal 36 is further depressed to cause the rod 28 to move upward with relation to the bracket 23 45 and the holding action of the spring 71 to pivot the bell crank 61, which in turn pivots the lever 59, which in moves the member 57 laterally to move the pin 30 laterally to engage the positioned pin into the materials which have been 50 bent over the cam 55 by the cam recess 56 formed in the bottom face of the member 23.

When the foot pedal 36 has been depressed as far as it will go the pin setting operation has been completed and the foot pedal 36 should be 55 released to permit the springs 25, 50 and 71 to draw the member 23, the rod 43 and the rod 28 back to their original positions, which is shown by the full lines in Fig. 5, and the dot and dash lines in Fig. 1. The next operation is to remove 60 the materials 12 and 13 from the table top 10 and this is accomplished by withdrawing the pin-sealed tie material from the holding strips, as aforesaid, to permit the materials to be sewed upon a conventional sewing machine, after which 65 the pins may be removed, or by hand, in which case the pins are removed while sewing.

While I have illustrated and described the preferred embodiments of my invention, it is to be understood that I do not limit myself to the 70 precise constructions herein disclosed and the right is reserved to all changes and modifications coming within the scope of the invention as defined in the appended claims.

Having thus described my invention, what I 75

claim as new, and desire to secure by United States Letters Patent is:

- 5 1. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards, means for 10 forming elevated portions in the folded material, and means for inserting pins into said elevated portions for holding said materials in folded position.
- 15 2. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards, and means for 20 inserting pins into said materials at spaced positions for holding said materials in folded position, said holding strips comprising end portions, hinges pivotally connecting said end portions to the ends of said table, and portions extending at right angles to said end portions and over which said covering material is adapted to be folded.
- 25 3. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards, and means for 30 inserting pins into said materials at spaced positions for holding said materials in folded position, said holding strips comprising end portions, hinges pivotally connecting said end portions to the ends of said table, and portions extending at right angles to said end portions and over which said covering material is adapted to be folded.
- 35 4. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards, and means for 40 inserting pins into said materials at spaced positions for holding said materials in folded position, said holding strips comprising end portions, hinges pivotally connecting said end portions to the ends of said table, and portions extending at right angles to said end portions and over which said covering material is adapted to be folded, said end portions being pivotally mounted so that said holding strips may be withdrawn from the latter-mentioned portions from between the folds after the pins have been inserted so that the materials may be sewn upon a conventional sewing machine, or by hand.
- 45 5. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards,

means for forming elevated portions in the folded material, and means for inserting pins into said elevated portions at spaced positions for holding said materials in folded position, said plate comprising a substantially flat member having an upturned edge by which the plate may be manually moved for folding said covering material over said holding strips.

5 6. An automatic pin setting device for holding materials for sewing, comprising a table having a guide gauge mounted thereon and against which a lining and covering material of a tie may be positioned, holding strips engageable over said lining and covering materials for holding said materials in position while said covering material is being bent, a plate slidably mounted on said table and having one of its edges engaging beneath said covering material to fold said covering material over said holding strips when said plate is manually moved rearwards, means for forming elevated portions in the folded material, and means for inserting pins into said materials at spaced positions for holding said elevated portions in folded position, said slidable mounting of said plate comprising downwardly projecting pins engaging elongated slots formed in the table for guiding the movements of the plate when it is moved rearwards and forwards.

10 7. In an automatic pin setting device for holding materials for sewing, a means for inserting pins in aligned covering and lining materials for a tie for holding said materials in position so that said materials may be sewed on a conventional sewing machine or by hand, comprising a table, a bracket pivotally mounted on the side of said table, a member pivotally mounted intermediate of its ends on said bracket and having an end extending over said table, a resilient means for holding said member and said bracket in relative positions, a rod slidable through the other end of said member, a stop pin for the bracket, means for moving said rod to pivot said bracket until it strikes said stop pin to limit its pivoting so as to next pivot said member on said bracket against the action of the resilient means until the bottom at the front of said member strikes against the said materials, pins in a pin supply in the first-mentioned end of said member, a pin holder mounted on said member and having opposed holding jaws for receiving and holding one pin, means for moving said pins downward from said pin supply to a position in which one of its ends will be between said jaws, and means for moving said pin laterally and operable only after said bracket and said member have ceased pivoting for forcing said pins into said materials for holding said materials in aligned positions so that they may be sewed on a conventional sewing machine, or by hand.

15 8. In an automatic pin setting device for holding materials for sewing, a means for inserting pins in aligned covering and lining materials for a tie for holding said materials in position so that said materials may be sewed on a conventional sewing machine, or by hand, comprising a table, a bracket pivotally mounted on the side of said table, a member pivotally mounted intermediate of its ends on said bracket and having an end extending over said table, a resilient means for holding said member and said bracket in relative positions, a rod slidable through the other end of said member, a stop pin for the bracket, means for moving said rod to pivot said bracket until it strikes said stop pin to limit its pivoting so as to next pivot said member on said bracket

bracket against the action of the resilient means until the bottom of said member strikes against the said materials, pins in a pin supply in the first-mentioned end of said member, a pin holder 5 mounted on said member and having opposed holding jaws for receiving and holding one pin, means for moving said pins downward from said pin supply to a position in which one of its ends will be between said jaws, and means for moving 10 said pin laterally and operable only after said bracket and said member have ceased pivoting for forcing said pins into said materials for holding said materials in aligned positions so that they may be sewed on a conventional sewing 15 machine, or by hand, said resilient means for holding said member and said bracket in relative positions comprising a screw passing through a portion of said bracket, an eye member attached to the bottom face of said member and a spring 20 extending between said screw and said eye member for urging said member rearwards to a position in which it will engage against the extended portion of said screw.

8. A device for inserting pins into a material, 25 comprising, in combination, a table having a portion thereof covered with a resilient facing, an upstanding element on the table surrounded by said resilient facing, a member pivotally mounted with an end in overlying relation to the said table, 30 provided at the said end with a clearance for the said upstanding element, and means for turning the said member to force its said overlying end into the said resilient table covering to fold the material on the said upstanding element.

35 9. The combination of claim 8 wherein the said member is provided at its said overlying end with means for inserting pins into the said folded material.

10. In a machine for inserting pins into a material, the combination of a table upon which a material is laid, a member pivotally mounted with one end in overlying relation to the said table, a pin reservoir contained in the said end of the member, means provided on the table and on the 40 said overlying end of the said member for operatively folding the material, and means for turning the said member to fold said material, to feed a pin from the said reservoir and to insert the fed pin into the said folded material.

50 11. In a pin inserting device. the combination

of a frame member provided with a reservoir for containing pins, a secondary smaller cavity and a discharge opening all in communication by passageways, a slide for feeding pins separately in a vertical direction through the said discharge 5 opening and means for projecting the said fed pin in a horizontal direction, comprising a horizontally movable member provided with a socket at one end for operatively engaging one end of the pin fed by the said slide through the said discharge opening.

12. In a device of the class described, in combination, a table upon which tie material is laid, means for holding the said material, means for folding the material upon the said holding means 15 and means for fastening the said folded material, the said holding means comprising a pair of strips pivoted at each end of the table with their distal ends in proximity, whereby the fastened tie may be withdrawn from the device by pulling its central portion upwards and turning the said strips 20 on their pivots.

13. A device for inserting pins into a material, comprising, in combination, a table upon which the material is laid, a member pivotally mounted 25 with one end in overlying relation to said table and said material, and means provided on the table and operative upon turning the said member for forming an upstanding fold in the said material, said means comprising an upstanding 30 element on the table, a portion of the said table being covered with a resilient facing surrounding said upstanding element, said overlying end of the said member being provided with a clearance for said upstanding element, whereby the said 35 overlying end may be forced into the resilient facing to fold the tie material on the said upstanding element.

14. In a device of the class described, in combination, a table upon which material is laid, pin 40 inserting mechanism positioned at spaced intervals along the material, and means for bringing the said mechanism into contact with the said material and for operating the said mechanism, the said mechanism being further provided with 45 instrumentalities for producing folds in the said material at spaced intervals, said last-mentioned means also operating said folding instrumentalities.

MORRIS S. MALEK. 50
